UNITED STATES PATENT OFFICE.

HARRY W. CODDINGTON, OF ROANOKE, VIRGINIA.

LOW-WATER ALARM.

Application filed December 26, 1924. Serial No. 758,148.

This invention relates to low water alarms of the thermostatic type and has among its objects to provide an improved device whereby the enginemen may be advised 5 when the water in a steam boiler reaches a dangerously low stage. A more specific object is to provide a thermostatically operated low water alarm having a maximum operating range for a given change in temperature, also to provide a low water alarm convenient to manufacture and easy to maintain in serviceable condition. A still further object is to provide a low water alarm especially adapted for use on locomotive boilers where the conditions of service are severe. With these general and other more specific objects in view, the invention 10 consists of the formation, combination and arrangement of parts as will be herein described and finally claimed.

In the accompanying drawings which show a preferred form of the invention, Figure 1 is an organization view showing a low water alarm constructed in accordance 15 with the principles of the present invention. This figure shows the alarm in side elevational view and as attached to the shell of an ordinary locomotive boiler. Figure 2 is a fragmentary, longitudinal, sectional view through the boiler end of the alarm. Figure 3 is a fragmentary, transverse, sectional view through a portion of the opposite end of the alarm, this view being taken 20 substantially on the line 3-3 of Figure 1. Figure 4 is a transverse, sectional view through one end of the expansion element, the view being taken on the line 4-4 of Figure 2. Figure 5 is a transverse horizontal sectional view through the boiler fitting 25 of the device, this view being taken substantially on the line 5-5 of Figure 2. Figure 6 is a transverse sectional view taken through another portion of the expansion element, this view being taken substantially 30 on the line 6-6 of Figure 1. Figures 7 and 8 are respectively a transverse vertical sectional view and a fragmentary side elevational view of the tube portion of the expansion element, these views showing a modified form of the bracket which supports 35 the fulcrum rod. Figure 9 is a plan view showing the upper portion of the boiler fitting to which the expansion ele-

ment is attached. The scale of Figure 1 is somewhat reduced over the scale of the remaining figures. 55

Before proceeding with a description of the device as illustrated in the drawings, it will first be mentioned that many difficulties and limitations are met in the construction 60 of thermostatic low water alarms, particularly those intended for use on locomotive boilers. The differences in temperature that are available and upon which operation depends are small. Every means is resorted to in order to obtain an increase in the thermal range, a gain of even a few degrees being sought after, and sometimes spelling the difference between a successful and an unsuccessful device. This will be better understood when it is remembered that a locomotive is exposed to a wide range of climatic conditions; is sometimes housed, again is exposed to rain or snow. The device should be capable of being applied to 70 and adjusted upon a cold boiler, not in motion, and must then be certain of operation on that boiler over a wide range of steam pressures and corresponding steam temperatures, whether the locomotive be standing 75 or running at high speed. The air temperature may vary from the highest extremes of mid-summer beneath a round house roof or the super-temperatures of tunnels, to the opposite extremes of winter. 80

Combined with these thermal conditions are others incident to the rolling and pitching action of the locomotive, due to the fact that railroad tracks are never true and are often undulating in surface. The locomotive is susceptible to rocking both transversely and longitudinally, which causes the water in the boiler to surge and momentarily change its level. While the alarm must be of a character to operate positively and 85 unmistakably to announce a condition of actual low water, it is of no less importance that it shall not sound false alarms as from merely a surge that momentarily uncovers the tell tale portion of the device. Delicate 90 thermal and mechanical problems are involved in the construction of any thermostatic low water alarm, where a limited temperature change and almost microscopic expansive movement must be utilized; and the 95 problems are, as stated, even greater for lo- 100

105

comotive service. The benefits derived from the various features of the present invention will be more clearly understood by having in mind these peculiar operating conditions.

- 5 Referring now to the drawings the shell of the boiler is denoted by the numeral 1. At any suitable point, preferably just above the point where it is desired to indicate a critically low stage of water, the shell of 10 the boiler is provided with an opening 2, the upper or outermost portion of this opening being beveled as indicated at 3. Seated from the exterior against this beveled portion of the opening is a ball faced ring 4 which is interiorly threaded, as indicated at 5, and into which is screwed a bushing 6. This bushing may extend inwardly 15 slightly within the steam cavity of the boiler, and is in turn interiorly threaded to accommodate a threaded drop pipe 7 which is connected thereto. The exterior surface of the lower end of the bushing 6 is formed with faces as indicated at 8 to accommodate the jaws of a wrench or other tool for screwing 20 it firmly into the ring 4 from the under side of the latter. After screwing the drop pipe 7 into the bushing 6 the uppermost end of the pipe may be beaded over as indicated at 9 to prevent unscrewing, and the pipe 7 25 may be welded to the bushing as indicated at 10 to effectively seal the threaded connection and prevent the loss of the vacuum within the cavity of the alarm. The drop pipe 7 will be carried down to the level 30 where it is desired that the alarm shall sound from the stage of the water.
- 35 Mounted upon the upper surface of the ring 4 is a special boiler fitting 11. A plurality of studs 14 are screwed into the shell 40 of the boiler and the upper ends of these studs extend through suitable openings in a bottom flange 15 of the fitting. The fitting 11 may, by means of the studs 14, be clamped firmly against the ring 4, the upper face of 45 the ring 4 and the bottom face of the fitting 11 being machined to constitute a flat steam tight joint 12. The upper surface of the ring 4 is also preferably provided with a machined cylindrical extension 13 which is 50 preferably arranged concentric with the bore of the ring 4, this cylindrical portion comprising a dowel adapted to seat within a suitably formed recess in the base of the fitting 11. By the inter-engagement of the 55 said recess and the dowel the fitting 11 is prevented from slippage with respect to the ring 4 and the dowel and recess may also comprise a portion of the steam tight joint between these two elements.
- 60 It has been found desirable to construct low water alarms of this type with the drop pipe indirectly connected to the fitting 11 in the manner shown, as the proper length of the drop pipe can be more accurately determined and set than with construction of

other types. It has also been found easier to keep steam tight joints by this construction inasmuch as the ring 4 may be made of one kind of material, the fitting 11 of another kind if desired, and the bushing 6 of still another kind of material. It has also been found easier to align the various parts in service when the ring 4 is made separately from the fitting 11 as illustrated.

65 It has already been pointed out that the available movement of the free end of the expansion element is very small, being in fact almost microscopic. It is accordingly necessary to mount and adjust the alarm upon the boiler with great accuracy, particularly the anchored end of the expansion element with respect to the bracket 34 and other associated elements at the operative end of the device. On the other hand, a locomotive boiler is known to those acquainted with the art as being subject to unusually large inaccuracies, due to its size and to the methods that must be employed in its manufacture. Furthermore, its great size and weight preclude the use on the same of tools of precision in connection with the mounting of the alarm. A peculiar use and advantage of the construction just described resides accordingly in the fact that the alarm may be thereby more accurately mounted upon the rough boiler, inasmuch as the drop pipe unit and the fitting 11 may be adjusted with respect to each other and the joint face 12-13 of the ring 4 may be slightly angled by accurate machine tools, so that by a slight rotation of the drop pipe unit, the outer end of the mechanism may be brought into delicate alignment, irrespective of boiler irregularities.

70 The fitting 11 has a substantially cylindrical cavity 16 arranged in vertical alignment with the drop pipe 7 and in direct open communication, through the cavity of the drop pipe 7, with the steam or water space of the boiler. This cavity extends upward for the full height of the fitting 11 and at the upper extremity is normally closed by means of a screw plug 17. Just below the top of the fitting the cavity 16 has a lateral branch 18 which is inclined slightly upward from the horizontal, and to the outer end of this branch is connected the sloping expansion element 19, the cavity of the expansion element being in open fluid communication with the cavities 16 and 18. The plug 17 is provided with a depending stem 20, on the lower end of which is formed a baffle or choke 21. This baffle comprises a disk which fits across the cavity 16 but is provided with one or more small openings such as 22. These are designed to give free access of steam to the cavity above the disk and to the cavity of the expansion element, serving at the same time to restrict the circulation of water between the cavity of the boiler and

the connected cavities above the openings 22. This baffle also serves to retard the fall of water from the expansion element in cases where the lower end of the drop pipe is momentarily uncovered, as by a surge of water in a locomotive boiler. Located slightly below the baffle 21 are a plurality of inwardly extending stops or shelves 23 formed upon the interior wall of the fitting 11. These are provided in order to prevent the disk 21 from dropping to a position where the top of the bushing 6 might be blanketed off in case the stem 20 should break. It will be noted in Figure 5 that in the present embodiment there are three of these shelves whereas there are but two of the openings 22. By making the number of shelves different from the number of openings, the openings can never simultaneously register with all of the shelves and the disk will thereby be prevented from ever dropping past the shelves while at the same time the shelves can never seriously interfere with the passage of steam and the slow passage of water through one or more of the openings 22.

It has been found by experiment that a baffle arranged at the location and in the manner just described is especially effective in preventing undue soundings of the alarm from surges. Its efficiency in this respect is due to the fact that when the water attempts to drop back suddenly through the openings 22, a localized vacuum tends to form in the space immediately above the baffle 21. Also, under certain circumstances steam becomes trapped in the portion of the chamber 16 that lies above the baffle 21, thus forming a seal for the water in the expansion element.

By integrally connecting the baffle 21 to the plug 17 it will be seen that when the plug is rotated in the unscrewing direction the baffle will be similarly moved. Accordingly if the baffle should be sealed to the interior of the fitting, it will be broken loose from the same and propelled outwardly through the incrustation by the rotation and retraction of the plug 17.

The outermost end of the branch of the fitting 11 which contains the cavity 18 is arranged for a ball joint connection with the boiler end of the expansion element 19. For this purpose this end of the fitting is beveled as indicated as at 24. The main portion of the expansion element is formed of a metallic tube with a collar 25 brazed or otherwise secured upon the outer periphery of the same. The end of the tube is expanded around the end of this collar as shown at 26 and the metal of the tube at the portion 26 thereof is then machined off to form, with the bevel 24, a steam tight joint. A spanner nut 27 is threaded upon the exterior surface of the branch of the fitting 11 and by means of this spanner nut

the boiler end of the expansion element is clamped tightly against the end of the branch of the fitting 11.

Firmly fixed in the interior of the boiler end of the expansion element 19 is a baffle 28 which in the present embodiment consists of three disks 29 which are substantially of the same diameter as the interior of the cavity of the tube portion of the expansion element. These disks are spaced somewhat from each other and are connected by means of suitable stem portions. Each disk is provided with an upper and a lower opening 30, these openings being designed and arranged to permit of the ready flow of steam to fill the cavity of the expansion element but to retard the return of water from the cavity of the expansion element to the boiler. It has been found preferable to rigidly and permanently affix this baffle in the boiler end of the expansion element. It has also been found permissible to do so inasmuch as it is not necessary to provide for means at the boiler end of the expansion element to wash out and cleanse the interior of the tube as scale and sediment do not lodge within it to any great extent in ordinary usage. It is accordingly preferable to mount these disks permanently in the lower end of the expansion element and to furnish expansion elements fitted with the baffles as a single manufactured unit. This construction also permits of the use of the stem 20 to connect the baffle 21 to the main portion of the plug 17 as the presence of the stem does not interfere with the baffle. It has been found necessary to occasionally wash out the drop pipe 7 and for this reason the opening in the fitting 11, normally closed by the plug 17, is maintained in alignment with the bore of the tube 7. When the plug 17 is unscrewed, the baffle 21 which is connected thereto by the stem 20 is withdrawn at the same time and direct access is had to the cavity of the drop pipe 7.

It will be noted in Figure 9 that index figures or match marks are provided on the top surface of the plug 17 and on the top edge of the adjacent portion of the fitting 11. It is the intention that the plug 17 shall be screwed into the fitting until the mark on the plug matches with the marks on the top of the fitting. This will insure the openings 22 of the baffle 21 standing in a transverse direction with respect to the line of the expansion element 19. At the same time, the baffle 28 is fixed in the tube portion of the expansion element in such manner that the openings 30 of the disks 29 will lie in vertical arrangement. Considering the channel of the member 11 and of the branch thereof, the holes 30 in the upper disks are out of axial alignment with the holes 22 of the disk 21. This arrangement still further breaks up the local circulation and

offers additional impedance to the water, with no great tendency for the relatively small openings to become clogged and without any measurable change in the resistance to the entrance of steam.

By arranging the baffle 21 substantially at right angles to the baffle 28 the thermal efficiency has been found to be increased a greater amount than by the addition of extra discs 29 to the baffle 28, as the right-angled arrangement of baffles breaks up the direct path of circulation of the water between the expansion element and the boiler, thereby resulting in a decreased temperature of the water within the expansion tube. And by arranging the openings 22 out of axial alignment with the openings 30 a still greater difference in temperature is obtained and the range of the alarm very materially increased.

It should be understood that while the isolated water in the expansion tube is sometimes referred to as being "chilled", this expression is relative only, for in fact the water in the expansion element under the most favorable conditions is many degrees higher in temperature than the surrounding atmosphere and often not many degrees below the boiler temperature. The steam engineer is aware that the temperature of the water inside of the boiler is the same as that of the steam itself. The drop pipe 7, being surrounded by steam, the water in the same is of practically equal temperature with the steam. And the thermic circulation within and between the several connected cavities of the low water alarm causes the isolated water in the expansion element to remain at a temperature closely approaching that of the steam unless means are introduced to break up and hinder such circulation. The provision of the baffle 21, and particularly the arrangement of the apertures 22 thereof with respect to the apertures 30 in the discs of the baffle 28 has been found to be particularly effective in this respect, due to the fact that the water is compelled to follow a spiral course in its circulation and sets up cross currents in the space next above the baffle 21 which tend to equalize the temperature of the water in this space, resulting in a break up of the general thermic circulation and causing a reduction in the temperature of the water in the expansion tube 19.

The outer end of the expansion element 19 comprises a terminal fitting 31. A portion of this fitting at 32 has a square external contour and this is arranged to rest in and to be supported by a jaw-shaped opening 33 in a bracket 34. The bracket 34 is shown as attached to the shell of the boiler by means of studs 35, with any suitable leveling means such as melted babbitt poured into the crevice between the bracket and the shell of the boiler, this being indicated at 36. The ex-

pansion element 19 is demountably attached to the fitting 11 as heretofore explained, and accordingly it may, when detached from the fitting 11, be lifted out of the jaw-shaped opening of the bracket 34. In order to prevent undesired lifting of the outer end of the expansion element, either by hand or during the operation of the device, a yoke member 35 is provided. The member 35 is attached to the bracket 34 by means of small bolts 36 and the member 35 is arranged to embrace the outer end of the terminal fitting 31 as indicated in the drawings, to form an upper guide for the same. The yoke 35 must, of course, be removed from the bracket 34 before the expansion element can be lifted out of the jaw-shaped opening. The outermost end of the fitting 31 may be closed by a plug 37. A test pipe 38 with a test valve 39 may be led out from the plug 37. The jaw of the bracket 34 forms a means to prevent injury to the expansion element when it is necessary to unscrew the plug 37. The main portion of the expansion element is usually formed of a relatively soft material such as a copper tube of relatively light gauge, and should the plug 37 be difficult to unscrew, the tube portion of the expansion element might be injured except for the protection of the jaw engagement of the outer end of the element with the bracket 34. The yoke member 35 is provided in order to prevent undesired lifting of the outer end of the expansion element. It has been found that in the absence of such guiding means a part of the available movement is lost, being expended in lifting of the outer end of the expansion element. The squared outer guide comprises means to prevent injury to the tube 19 when the plug 37 is unscrewed. At the same time the removable yoke member 35 makes it possible to readily disassemble the device and also conserves the available movement as heretofore mentioned by directing it in the desired direction and preventing rising of the outer end of the expansion element.

Low water alarms of this type are actuated by thermal expansion and contraction of the expansion element. As long as the open lower end of the drop pipe 7 is submerged the drop pipe itself, the fitting 11, the tube portion of the expansion element 19, and the terminal portion 31 thereof will all be filled with water. This water is isolated from the water of the boiler and with the introduction of the baffles near the boiler end of the expansion element as heretofore described, local circulation will be practically prevented, so that the water in the expansion element will be at a considerably lower temperature than the water within the boiler. As soon as the lower end of the drop pipe 7 is uncovered, the water in the expansion element will tend to fall back into the boiler,

and if the lower end remains uncovered for a short period of time the water will all leave the expansion element and it will be replaced by steam of a temperature corresponding to the boiler pressure. The expansion element 19, and a portion of the fitting 11, will accordingly lengthen in response to the thermal change and, as the fitting 11 is rigidly connected to the boiler shell, whereas the outer end of the expansion element is free to slide longitudinally in the bracket 34, it will be seen that the outer end of the expansion element will move in response to the lengthening of the parts. This movement is taken advantage of to actuate an alarm lever 40 which is pivotally attached to the terminal fitting 31 at 41. This feature of the device is not new, but in the past it has been the practice to fulcrum the lever such as 40 directly upon the bracket 34. The result of this has been, that, considering the device to have been fitted up and adjusted with the boiler cold, which is the usual practice, much of the expansive value of the expansion element has been lost, inasmuch as the shell of the boiler lengthens when the boiler is fired up and the shell becomes heated. A feature of the present invention is to overcome this defect and at the same time to increase the range of the expansion element. The general principle involved in correcting the defect is to arrange a fulcrum for the lever 40 which will not be affected by the expansion and contraction of the boiler shell. To do this for a boiler of the type shown it is desirable to carry the fulcrum back as near to the boiler end of the expansion element 19 as practical. In the present embodiment, the fulcrum point for the lever is indicated at 42. Extending from the point 42 to the fitting 11 is a tie-rod 43 having a suitable jaw at the fulcrum end and being threaded into a bracket 44 of the fitting 11 at the opposite end. Inasmuch as the fitting 11 is in effect a portion of the expansion element, its expansion and contraction being effective to actuate the lever 40, the same as though it were an integral part of the expansion element, it will be seen that the fulcrum thus described is in effect located upon or attached to the boiler end of the expansion element. The rod 43 is preferably guided from the tube portion of the expansion element by means of a guide 45. This prevents vibration of the rod 43 when the locomotive is in operation. It will accordingly be seen that whereas the bracket 34 supports the outer end of the expansion element, the lever 40 is in turn supported, not by the bracket 34, but by the expansion element through the connection 41, and that when the point 41 moves to the left (see Figure 1) in response to lengthening of the parts the point 42 will not be similarly affected and the result will be a downward movement of the extreme outer end of the lever 40, which is provided with a suitable contact stud 46. The stud 46, contacting with the stem 47, of a steam valve 48 which is mounted upon the bracket 34, will cause this valve to open and will admit boiler steam from the pipe 49 to the pipe 50 and thence to the alarm whistle 51. The pipe indicated at 52 beneath the whistle is for drainage purposes only. When the water level is restored and the trapped steam in the expansion element 19 and the connected chambers has condensed, water from the boiler will be drawn up into the various connected passageways. As this isolated water cools the expansion element will again contract and the lever 40 will be retracted, permitting the valve 48 to close thereby shutting off the alarm.

By means of the test valve 39 the device may be tested for complete operation. By opening this valve for a few seconds the chilled water will be blown out of the expansion element and connected parts and the connected passageways will be filled with hot water from the boiler, which being at substantially the same temperature as the steam, the entire device will be actuated the same as though the passageways were actually filled with steam. The pipe 38 preferably discharges into the ash pan.

In Figures 1 and 6 the guide 45 for the rod 43 is shown as entirely surrounding the tube of the expansion element and brazed or otherwise rigidly secured thereto. In the embodiment shown in Figures 7 and 8 the guide is arranged to clamp around the expansion element, using a clamping bolt 53. In order to correctly position the guide with respect to the tube, a feather 54 may be brazed or otherwise formed upon the tube. The ends or another suitable portion of the guide may contact with this feather to insure the guide being in proper position to receive the rod 43.

I have thus described a preferred form of my invention. Other embodiments are contemplated, within the scope of the appended claims, without departing from the spirit thereof.

What is claimed is:

1. A low water alarm of the thermostatic type, the same including in combination with a steam boiler, a fitting attached to the boiler, said fitting having a passageway therein, an expansion element in fluid communication with one end of said passageway, a drop pipe connected to and in fluid communication with the other end of said passageway, the same being arranged in axial alignment with said passageway, said drop pipe extending within the steam and water space of the boiler and terminating in an open lower end defining the critical stage of the water, and a baffle arranged across the said passageway of the fitting, the baffle

lying above and in line with the said drop pipe.

2. A low water alarm of the thermostatic type, the same including in combination with 5 a steam boiler a fitting attached to the boiler, said fitting having a passageway therein, an expansion element in fluid communication with one end of said passageway, a drop pipe connected to and in fluid communication with 10 the other end of said passageway, said drop pipe extending within the steam and water space of the boiler and terminating in an open lower end defining the critical stage of the water, a baffle arranged across said passageway, the baffle lying above and in line with the said drop pipe, a clean-out opening in the fitting above and in line with the baffle, and a member adapted to normally close said opening, the baffle being attached 15 to said closing member.

3. A low water alarm of the thermostatic type, the same including in combination with 20 a steam boiler a fitting attached to the boiler, said fitting having a passageway therein, an expansion element in fluid communication with one end of said passageway, a drop pipe connected to and in fluid communication with the other end of said passageway, said drop pipe extending within 25 the steam and water space of the boiler and terminating in an open lower end defining the critical stage of the water, a baffle arranged across said passageway, the baffle lying above and in line with the said drop pipe, a clean-out opening in the fitting above and in line with the baffle, a member adapted to normally close said opening, the baffle being attached to said closing member, and means formed on the interior wall of the 30 fitting comprising an emergency support for 40 said baffle.

4. A low water alarm of the thermostatic type including, in combination with a boiler, a boiler fitting having a cavity in fluid communication with the steam and water space 45 of the boiler, an expansion element connected to the fitting and extending laterally therefrom, the same being in open fluid communication with the cavity of the fitting, a 50 baffle in the expansion element near the said fitting, and a baffle in the cavity of the fitting, the said baffles being arranged in planes substantially at right angles to each other.

5. A low water alarm of the thermostatic type including, in combination with a boiler, an expansion element, means for connecting the expansion element with the steam and water space of the boiler, the same comprising, with the fluid cavity of the expansion 55 element, an open fluid passageway, and a series of baffles arranged in spaced relation to each other across the said fluid passageway, said baffles being located near the boiler end of the expansion element and 60 comprising cross walls having openings 65

therein, some of the openings being arranged out of line, axially of the passageway, with others thereof.

6. In a low water alarm of the thermostatic type, the combination with a steam 70 boiler of a drop pipe adapted to extend within the steam and water space thereof, a collar secured to the upper end of the drop pipe, the said collar being arranged to co-operate with the boiler shell to form a steam-tight joint, a fitting removably mounted upon the collar, and an expansion element 75 extending laterally from said fitting and removably secured thereto, said fitting comprising a fluid connection between the drop pipe and the expansion element.

7. In a low water alarm of the thermostatic type, the combination with a steam 80 boiler of a drop pipe adapted to extend within the steam and water space thereof, a collar secured to the upper end of the drop pipe, the said collar being arranged to co-operate with the boiler shell to form a steam-tight joint, a fitting removably mounted upon the collar, an expansion element extending laterally from said fitting and removably secured thereto, said fitting comprising a fluid connection 85 between the drop pipe and the expansion element, and means connected to the shell of the boiler adapted to clamp the said fitting to the collar and the collar against the boiler.

8. A low water alarm of the thermostatic type including in combination with a steam 90 boiler a drop pipe extending from the exterior of the boiler into the steam space thereof and having an open lower end defining the critical stage of the water, a hollow fitting 95 mounted upon the boiler in open fluid communication with the said drop pipe, an expansion element extending from and in open fluid communication with said hollow fitting, a removable baffle arranged across the cavity of said hollow fitting above and in line with said drop pipe, and a normally closed clean-out opening in the fitting above and in line with the baffle.

9. A low water alarm of the thermostatic type including in combination with a boiler 100 a fitting attached thereto, an expansion element demountably attached to the fitting, a support bracket for the outer end of the expansion element, the same having a recess formed therein adapted to receive the expansion element, and a removable member 105 secured to the bracket and engaging the end of the expansion element, the walls of said recess and the said member being arranged to guide the expansion element.

10. A low water alarm of the thermostatic type including in combination with a boiler 110 a fitting attached thereto, an expansion element demountably attached to the fitting, a support bracket for the outer end of the expansion element, the same having a non-cir- 115 120 125 130

cular recess formed therein adapted to receive and guide the expansion element and to hold the same against rotation axially of the expansion element, the outer end of the expansion element being of co-operating non-circular cross section, and removable means attached to the bracket and overlying the ex-

pansion element, the same being adapted to co-operate with the outer end of the expansion element to hold the same against rising ¹⁰ from normal position within said recess.

In testimony whereof I affix my signature.

HARRY W. CODDINGTON.
